Specification for Design.

Patented July 15, 1919.

Application filed March 24, 1919. Serial No. 284,880. Term of patent 14 years.

To all whom it may concern:

Be it known that I, JACOB A. MARCMANN, a citizen of the United States, residing at Irvington, county of Essex, and State of New Jersey, have invented a new, original, and ornamental Design for Wrenches, of which the following is a specification, reference being had to the accompanying drawing, forming part thereof.

Figure 1 is a perspective view of the improved ornamental wrench, and

Fig. 2 is a similar view showing the end and the faces of the wrench not disclosed in Fig. 1.

I claim:

The ornamental design for a wrench, as shown.

JACOB A. MARCMANN.
